UNITED STATES PATENT OFFICE.

FRED B. COREY, OF SCHENECTADY, NEW YORK, ASSIGNOR TO GENERAL ELECTRIC COMPANY,
A CORPORATION OF NEW YORK.

BLOCK-SIGNAL SYSTEM.

No. 909,158.

Specification of Letters Patent.

Patented Jan. 12, 1909.

Application filed March 30, 1908. Serial No. 424,036.

To all whom it may concern:

Be it known that I, FRED B. COREY, a citizen of the United States, residing at Schenectady, county of Schenectady, State of New York, have invented certain new and useful Improvements in Block-Signal Systems, of which the following is a specification.

My invention relates to block signal systems employing "three position" signals; 10 that is, systems in which the signal arms are arranged to assume three distinct positions to indicate "danger", "caution" and "clear", respectively. In such a system it is customary to employ contacts on each signal to 15 control the movement of the signal next in the rear from "caution" to "clear" position. This control is ordinarily performed through a line relay, sometimes termed a "three position" relay, placed at the signal in the rear. 20 It has furthermore been customary to construct three position signals with a stationary lock magnet, or some similar device, so that the signal may be stopped in "caution" position, when it is moved from "clear" position by a train backing into the block in advance and thereby putting the signal for the block in advance from "caution" to "danger" position. With some signal mechanisms, however, as for instance such a signal 25 mechanism as is described in my Patent #868,648 issued October 22nd, 1907, it is not possible, conveniently, to provide means for stopping the signal in an intermediate position when moving from "clear" toward 30 "danger". It therefore becomes necessary when the signal is to move from "clear" to "caution", to allow it to move first to "danger" position momentarily and then to return to "caution". In a signal operating in 35 this manner, however, it has not heretofore been practicable any longer to control the signal in the rear from contacts on the signal shaft, since if a train should back into one block putting the signal at "danger", it 40 would throw the signal for the block next in the rear, from "clear" to "caution", but in making this movement the signal for the block in the rear, having to move momentarily to "danger" position, would throw the 45 next signal behind it from "clear" position momentarily to "danger", and this action might be repeated for the entire length of the road. For this reason, when signals of the 50 type described in my former patent have 55 been operated as "three position" signals; it

has been customary to control the movement of each signal from "caution" to "clear" and vice versa, not by contacts on the shaft of the signal in advance, but by contacts on the track relay for the block in advance. 60 This, however, is objectionable, because, if a block is clear but the signal mechanism out of order, the signal for that block might stand at "danger" with the signal next in the rear at "clear". That is, each signal no 65 longer under all conditions accurately indicates the condition of the signal in advance and the failure of a signal mechanism may result in forcing each train approaching it to make an emergency stop in order to avoid 70 running past it.

By means of my invention I am enabled to control each signal by contacts on the signal mechanism itself of the block next in advance and yet to avoid throwing a series of 75 signals to "danger" behind a train when it backs into a block. I accomplish this by providing means for rendering the contacts on the signal shaft inoperative to control the signal next in the rear when the first mentioned signal goes momentarily to "danger" in moving from "clear" to "caution". More specifically stated, I provide means for short-circuiting the contacts when the driving motor of the signal is in operation. 80

My invention will best be understood by reference to the drawing which shows diagrammatically a signal system arranged in accordance with my invention.

In the drawing, A, A¹ and A² represent the 90 rails of three successive blocks supplied with current from track batteries B, B¹ and B². The block A is shown occupied by a train and the direction of traffic is indicated by an arrow.

C, C¹ and C² represent track relays for 95 three blocks, the relay C being deenergized, and the other two being energized since their blocks are "clear".

D, D¹ and D² represent the signals for the 100 blocks. These are "three position" signals, the signal D being shown at "danger" position, the signal D¹ at "caution" and the signal D² at "clear". The signal mechanisms are shown diagrammatically; their construction may be identical with that described in my former patent No. 868,648 above referred to.

E represents the driving motor for the 105 signal D. This motor is provided with a 110

main series field e , a shunt field e^1 for the purpose of electric braking.

The clutch, or slot mechanism is indicated at F. This mechanism may be provided 5 with an auxiliary series winding f.

G represents the line or "three position" relay which controls the movement of the signal from "caution" to "clear".

H represents the switch contacts which 10 move with the signal arm. These contacts would, in practice, be placed on the signal shaft, and would be constructed substantially as shown in my prior patent, but for the sake of clearness in illustration I have 15 shown the contacts developed on a plain surface. There are nine stationary contacts h to h^8 and movable contacts as shown.

I represents the battery, or the source of 20 current for supplying the signal mechanism.

J represents a relay connected in series 25 with the motor and arranged to short-circuit the pair of contacts h and h^1 .

The operation of the system is as follows: 30 As long as the car or train remains in block A, the signals will remain in the position shown. When the train passes out block A, track relay C is energized and closes the circuit from the left hand terminal of the battery through relay J, series clutch magnet winding f, motor field e, motor armature E, contacts h^3 , h^4 and h^7 and armature of track relay C, to right hand terminal of battery I. The circuit of the shunt winding F of the clutch or slot magnet is closed through contacts h^5 , h^6 and h^7 and the contact of track relay C. Both motor and slot magnet are consequently energized and the motor begins to drive the signal from "danger" position. When the "caution" position is 40 reached the circuit connections become the same as are shown for signal D¹. The circuit of the motor is open at contact h^4 so that the signal arm comes to rest, the circuit of the shunt winding of the slot magnet being kept closed. While signal D has 45 thus been moving from "danger" to "caution" position, signal D¹ has been moving from "caution" to "clear" position, because since the circuit of the motor E is closed, relay J in series with it is energized, thereby closing a circuit from the left hand terminal of battery I through the armature of relay J, through the upper line wire to line relay G¹ back through the lower line wire and through 50 armature of track relay C to right hand terminal of battery I. Line relay G¹ is consequently energized and closes the circuit from the left hand terminal of battery I through relay J¹ slot magnet f¹, series field e, armature E¹, contacts h^3 , h^8 , armature of relay G¹, and armature of relay C¹ to the right hand terminal of battery I¹. Signal D¹ is therefore driven from "caution" to "clear" position. When "clear" position is reached the 55 circuit connections become the same as those

shown in signal D². The motor is disconnected from the battery at contact h^3 but is short-circuited through contacts h^4 and h^2 , and therefore, because of its shunt field, acts as an electric brake to bring the signal arm 70 quickly to rest. This electric brake action, which is described at greater length in my prior patent above referred to, is, in the present system, employed only at "clear" 75 position, since at the intermediate or "caution" position a difference of one or two degrees in the stopping point of the arm is not of sufficient importance to warrant the added complication of braking the motor at this point.

Although the relay J is energized only while the motor E is in operation, the line relay G¹ is not deenergized when the signal D reaches "caution" position and the circuit of motor E is opened because before this 80 time the circuit of line relay G¹ has been closed by the contacts h and h^1 of switch H. So far as the movement of the signals from "danger" to "caution" and to "clear" is concerned, the relay J performs no useful 85 function except to cause the signal D¹ to start its movement from "caution" to "clear" simultaneously with the movement of the signal D from "danger" to "caution". It is upon the reverse movement of the signals that the operation of the relay J becomes of importance.

Suppose that the train, after leaving block A backs into this block again, thereby returning signal D to "danger" position; this 100 opens the circuit of line relay G¹ and allows signal D¹, which had been cleared, to start back again toward "danger" position. Since the signal mechanism is not constructed so as to catch the signal arm at "caution" 105 position, its movement must be continued until "danger" position is reached; the motor then immediately returning the arm to "caution" position. If it were not for the relay J¹ the signal D² would be thrown momentarily to "danger" by the movement of signal D¹ to "danger", and similarly the signal in the rear of D², and all the remaining signals on the road might be thrown to "danger". Relay J¹, however, prevents 110 this from occurring, for, before contacts h and h^1 have been opened by their movable contacts, the circuit of motor E¹, and consequently relay J¹ has been closed at contacts h^3 , h^4 and h^7 . The relay J¹ is therefore energized and pulls up its armature to short-circuit contacts h and h^1 before their circuit is opened at their movable contacts. Thus the contacts h h^1 of switch H¹ are rendered 120 inoperative to open the circuit of line relay G² when signal D¹ goes only momentarily to "danger" and motor E¹ is in operation to drive it back to "caution".

I do not desire to limit myself to the particular construction and arrangement 130

parts shown in the drawing, but aim in the appended claims to cover all modifications which are within the scope of my invention.

What I claim as new and desire to secure by Letters Patent of the United States, is,—

1. In a signal system, a signal arm adapted to assume three distinct positions, a motor for moving said arm, contacts controlled by the movement of said arm controlling the signal next in the rear, and means for rendering said contacts inoperative to control the signal in the rear when said motor is in operation.
2. In a signal system, a signal arm adapted to assume three distinct positions, a motor for moving said arm, contacts controlled by the movement of said arm controlling the signal next in the rear, and means for short-circuiting said contacts when said motor is in operation.
3. In a signal system, a signal arm adapted to assume three distinct positions, an electric motor for moving said arm, contacts controlled by the movement of said arm controlling the signal next in the rear, and a relay in circuit with said motor adapted when energized to render said contacts inoperative to control the signal in the rear.
4. In a signal system, a signal arm adapted to assume three distinct positions, an electric motor for moving said arm, contacts controlled by the movement of said arm controlling the signal next in the rear, and a relay in circuit with said motor adapted when energized to short-circuit said contacts.
5. In a signal system, a signal arm adapted to assume three distinct positions to indicate "danger", "caution", and "clear", a motor for moving said arm, a line relay controlling said arm in its "clear" position, contacts in circuit with the line relay of the signal next in the rear arranged to open said circuit when said arm is at "danger" and to close it when said arm is at "caution" or
- "clear", and means for rendering said contacts inoperative to open said circuit when said motor is in operation.
6. In a signal system, a signal arm adapted to assume three distinct positions to indicate "danger", "caution" and "clear", an electric motor for moving said arm, a line relay controlling said arm in its "clear" position, contacts in circuit with the line relay of the signal next in the rear arranged to open said circuit when said arm is at "danger" and to close it when said arm is at "caution" or "clear", and a relay in circuit with said motor arranged when energized to short-circuit said contacts.
7. In a signal system, a signal arm adapted to assume three distinct positions to indicate "danger", "caution" and "clear", contacts controlled by the movement of said arm and controlling the signal next in the rear to cause it to move from "caution" to "clear" when said arm moves from "danger" to "caution", and means for preventing said contacts from affecting the signal in the rear when said arm goes momentarily to "danger" in moving from "clear" to "caution".
8. In a signal system, a signal arm adapted to assume three distinct positions to indicate "danger", "caution" and "clear", contacts controlled by the movement of said arm and controlling the signal next in the rear to cause it to move from "caution" to "clear" when said arm moves from "danger" to "caution", and means for short-circuiting said contacts when said arm goes momentarily to "danger" in moving from "clear" to "caution".

In witness whereof, I have hereunto set my hand this 27th day of March, 1908.

FRED B. COREY.
